J. L. LINDER

SWIMMING GLOVE

Filed Aug. 6, 1927

Inventor
J. L. Linder

By *Lacey, Lacey*, Attorney

UNITED STATES PATENT OFFICE.

JOHN L. LINDER, OF PALO ALTO, CALIFORNIA.

SWIMMING GLOVE.

Application filed August 6, 1927. Serial No. 211,225.

This invention relates to swimming apparatus and more particularly to a glove intended to be worn while swimming and facilitate progress through the water.

5 One object of the invention is to provide a glove which may be worn in the usual manner and includes webs extending between the fingers so that when swimming the fingers may be spread and thereby provide a 10 larger surface to act upon the water and permit a person to swim with greater ease and rapidity.

Another object of the invention is to provide the thumb and fingers of the glove with 15 openings bordered by outstanding compressible ribs so that when a ladder, float or the like is grasped a suction may take place which will prevent the swimmer from losing his grip with resulting danger of slipping and possibly injuring himself.

The invention is illustrated in the accompanying drawing, wherein

Figure 1 is a view in elevation showing the glove when looking at the palm or inner 25 face thereof;

Fig. 2 is a longitudinal sectional view through the glove taken on the line 2—2 of Fig. 1, and

Fig. 3 is an enlarged transverse sectional view through one of the fingers taken on the line 3—3 of Fig. 1.

The improved glove includes a body 1 which may be formed of silk or any light water-proof fabric but is preferably formed 35 of rubber and carries the usual finger stalls 2 and thumb stall 3 formed of the same material as the body. The palm of the glove is provided with an enlarged opening 4 and at its rear the body carries straps 6 and 7 40 which are preferably formed integral therewith and intended to be releasably connected by a buckle 8. The buckle is preferably of the friction type so that the strap 6 may be drawn through it to retain the glove in place upon the hand. Each of the stalls is formed with an opening 9 adjacent its outer 45 end and the finger stalls are provided with other openings 10 intermediate the openings 9 and their inner ends. From an inspection 50 of Fig. 2, it will be seen that the openings in the stalls are so located that when the glove is worn the fingers and thumb may close the inner ends of these openings when

a ladder rung or other object is grasped. It should also be noted that there has been 55 provided ribs 11 which extend about the outer ends of the openings. These bordering ribs are formed of soft rubber which is easily compressible so that when a ladder rung is grasped the pressure applied will 60 create a vacuum in the openings and thereby prevent danger of slipping. When the hand is released, the fingers readily move away from the inner ends of the openings thereby 65 breaking the vacuum. It will, therefore, be seen that a very firm grip can be obtained upon a ladder or other object but that easy release of the object grasped will not be interfered with. Webs 12 which are also formed of rubber extend between the stalls 70 and may be formed integral therewith or separate from the stalls and suitably secured thereto in any desired manner. These webs are of such dimensions that the fingers and thumb may be spread as far as desired when 75 swimming and when the fingers and thumb are so spread the webs will provide additional surfaces to act against the water. It will thus be seen that a glove provided with these webs will permit a person to swim 80 very easily and at an increased rate of speed.

Having thus described the invention, I claim:

1. A swimming glove comprising a body adapted to fit about the hand and having 85 thumb and finger stalls provided with openings to be closed at their inner ends by portions of the thumb and fingers of the wearer, sealing members of soft material encircling the outer ends of the openings and projecting 90 from the outer surfaces of the stalls, and webs extending between said stalls.

2. A swimming glove comprising a body adapted to fit about the hand and having 95 thumb and finger stalls provided with openings to be closed at their inner ends by portions of the thumb and fingers of the wearer, sealing ribs of soft elastic material encircling the outer ends of the openings and projecting 100 from the outer surfaces of the stalls, and webs joining said stalls.

3. A swimming glove comprising a body adapted to fit about the hand and having thumb and finger stalls, the palm portion of the glove being open and said stalls having 105 openings intermediate their ends and adja-

cent their outer ends, sealing ribs of soft rubber projecting from the outer surfaces of the stalls in encircling relation to the openings, and webs joining said stalls.

4. A swimming glove comprising a body adapted to fit about the hand and having thumb and finger stalls provided with open-

ings to be closed at their inner ends by portions of the thumb and fingers of the wearer, and sealing ribs of soft rubber projecting from the outer surfaces of the stalls in encircling relation to the openings.

In testimony whereof I affix my signature.

JOHN L. LINDEER. [L. s.]
